UNITED STATES PATENT OFFICE.

EARL E. CHAPMAN, OF LOS ANGELES, CALIFORNIA, ASSIGNEE TO MILLER-CHAPMAN COMPANY, A CORPORATION OF CALIFORNIA.

WEIGHT-LIFTING DEVICE.

1,339,814.

Specification of Letters Patent.

Patented Sept. 6, 1921.

Application filed June 28, 1920. Serial No. 382,509.

To all whom it may concern:

Be it known that I, EARL E. CHAPMAN, a citizen of the United States, residing at Los Angeles, in the county of Los Angeles and State of California, have invented a new and useful Weight-Lifting Device, of which the following is a specification.

My invention relates to power multiplying devices.

10 The principal object of my invention is to produce a device by which a man may exert a heavy pull over a short distance by exerting a smaller pull on a lever moving over a greater distance.

15 My invention is adapted to the lifting of weights or for exerting pulls in a horizontal or other direction.

In the drawings I show a device which is especially adapted for lifting weights but 20 this device may be used for exerting a pull in other directions than the vertical, if desired.

A further object of the invention is to 25 provide a device which will not only lift a weight but which is so constructed that it works automatically to either lift or lower the weight.

Referring to the drawings which are for 30 illustrative purposes only,

35 Figures 1, 2, 3 and 4 are side elevations of the device in various positions as will hereinafter be explained.

Fig. 5 is a side elevation partly in section. 40 Fig. 6 is a perspective view of the cams.

Fig. 7 is a section on a line 7—7 of Fig. 1.

In the embodiment of my invention shown in the drawing, 11 is a chain which may be attached to any sort of a fixed support. While I have shown a chain as this 45 fixed or suspended member, any other member of irregular contour such as a rod with knobs thereon or a notched bar may be used without departing from the spirit of my invention.

Engaging the chain 11 are two hooks 12 and 13, these hooks being each formed of two bars 14 as shown in Fig. 5 joined together by a spacing member 15 near the top and pivoted near the bottom on pins 16 and 50 17 on a lever 18 which carries a suspension member 19 pivoted on a pin 20. The weight to be lifted is attached to the suspension member 19. Secured on the hook 13 is an arm 25 carrying a flat spring 26 which 55 presses on the hook 12 tending to force the

hooks 12 and 13 together. Loosely mounted on pins 30 between the members 14 of the hook 12 is a finger 31 which is held over by a flat spring 32 as shown in Fig. 7 and as will hereinafter be explained more in detail. The finger 31 projects between the side members 14 of the hook 12 and engages a member 40 having two cams formed thereon, namely, a lifting cam 41 and a lowering cam 42. These cams are somewhat similar in shape, the cam 42, however, having an inclined interrupted portion near the center thereof as shown in Fig. 7. The spring 32 is so placed that it tends to hold the end of the finger 31 in the path of the lowering cam 42. The function and relationship of the various parts will be best understood if the method of operation is explained as follows:

The chain 11 being attached to some rigid support, not shown, it is desired to exert a pull on the suspension member 14 either in a vertical direction for lifting a weight or some other direction for some other purpose. The operator places a pipe member 60 over one of the ends 61 of the lever 18 exerting a downward pressure thereon, the parts being in the position shown in Fig. 1. The hook 12 is in engagement with one of the links 70 of the chain 11 and the lever 18 moves around the pivot 17 lifting the hook 18 from the position shown in full lines in Fig. 1 through the position shown in dotted lines in that figure. As the hook 18 starts to rise, the finger 31 slides over the cam 41 forcing the hook 18 outwardly. This hook moves in a path indicated by the dotted line 63 in Fig. 1, being finally forced inwardly by the spring 26 to engage a link 64 in the chain 11 next above the link 65 originally engaged.

It should be noted that as the hook 18 approaches the position shown in Fig. 2 that it moves inwardly due to the shape of the cam 41, finally snapping over the link 64 under the influence of the spring 26. If now the operator lifts upon the pipe 60 the lever 18 pivots around the pin 16 passing from the full line position shown in Fig. 2 into the dotted line position shown in that figure, the hook 12 moving outwardly due to the action of the finger 31 and the cam 40. The hook, therefore, is disengaged from the link 70 on which it was originally caught, moving up and engaging the link 65 previously engaged by the hook 18. It will

thus be seen that by an alternate up and down movement that the whole device is advanced one link of the chain 11, the suspension member 19 being raised a distance 5 equal to the length of one pair of links of the chain 11. To raise this hook this small amount, the operator must exert a force over considerable distance both up and down. If it is desired to continue the movement, the 10 operation just described is repeated as many times as desired.

It will be noted that by the use of the finger 31 and the cam 40 that the outward and inward movement of the hooks is entirely automatic, these hooks moving out of engagement with the chain 11 and back into engagement following the lines of the cam 40. With the parts in the position shown in full lines in Fig. 1, if it is desired to lower 15 the weight, the operator pushes upwardly on the pipe 60 moving the parts into the position shown in Fig. 3. It will be noted that in this figure the hook 12 is raised out of engagement with the link 65 and it will 20 be further noted that the finger 31 is moved up into a position where it can snap over and engage the lifting cam 42, the spring 32 forcing it over against the side bar 14 of the hook 13. If now the operator allows the 25 pipe 60 to go downwardly by releasing his pressure thereon, the hook 12 is thrown outwardly by the cam 42 so that it clears the link 65 on its downward path, this hook moving downwardly until it resumes the position shown in Fig. 2. At the middle of its 30 travel, the finger 31 reaches the inclined portion 43 of the cam 42 and the pressure of the spring 26 forces this finger downwardly against the cam 41 upon which the finger 35 thereafter travels thus allowing the hook 12 to move inwardly sufficiently to engage the link 70. The operator then pushes downwardly on the pipe 60 lifting the hook 13 into the position shown in Fig. 4 which is 40 out of engagement with the link 64, the finger 31 being then in a position to engage the 45 lower end of the lowering cam 42. By diminishing his pressure on the lever 60 the operator can now allow the load to fall, the 50 hook 13 being thrown out of the path 64 as it moves downwardly. As it reaches its central position the finger 31 reaches the interrupted portion 43 of the cam 42 and the spring 26 forces the finger inwardly 55 against the cam 41 upon which it then travels. This allows the finger 13 to engage the link 65.

During the movements just described, the weight is lowered the length of one pair of 60 links in the chain and this lowering movement may be repeated as many times as desired by repeating the cycle of operation just described. It is thus possible for an operator to either raise or lower the weight 65 without in any way changing the device or

making any adjustments therein. If he wishes to lower, it is simply necessary to make a short reverse movement sufficient to move the finger 31 into engagement with the lowering cam 42, the finger then travels 70 upon the lowering cam and the weight may be lowered. In practice the operation of the device is very rapid and is extremely sure, the method of operation being readily learned and understood by anyone. 75

I claim as my invention:

1. A weight lifting device comprising a suspended member having projections thereon, a lever to which the weight to be lifted is attached, two hooks pivoted to said lever 80 on opposite sides of the attachment point of said weight, said hooks engaging the projections on said suspended member from opposite sides, spring means for forcing said hooks toward each other, and cam means for 85 forcing said hooks apart to disengage them from said suspended member.

2. A weight lifting device comprising a suspended member having projections thereon, a lever to which the weight to be lifted is 90 attached, two hooks pivoted to said lever on opposite sides of the attachment point of said weight, said hooks engaging the projections on said suspended member from opposite sides, and means for causing said 95 hooks to engage and disengage said irregularities.

3. A weight lifting device comprising a suspended member having projections thereon, a lever to which the weight to be lifted 100 is attached, two hooks pivoted to said lever on opposite sides of the attachment point of said weight, said hooks engaging the projections on said suspended member from opposite sides, spring means for forcing said 105 hooks toward each other, a finger secured to one of said hooks, and a cam secured to the other hook, said finger pressing against said cam which is so shaped as to force said finger to separate said hooks as it slides over said 110 cam.

4. A weight lifting device comprising a suspended member having projections thereon, a lever to which the weight to be lifted is attached, two hooks pivoted to said lever 115 on opposite sides of the attachment point of said weight, said hooks engaging the projections on said suspended member from opposite sides, spring means for forcing said hooks toward each other, and means for throwing each of said hooks away from said member as it is lifted by a movement of said lever about the pivot point of the other hook. 120

5. A weight lifting device comprising a suspended member having projections thereon, a lever to which the weight to be lifted is attached, two hooks pivoted to said lever on opposite sides of the attachment point of said weight, said hooks engaging the projections on said suspended member from oppo- 125 130

- site sides, spring means for forcing said hooks toward each other, and means for forcing each of said hooks away from said member as it is lowered by a movement of said lever about the pivot point of the other hook.
6. A weight lifting device comprising a suspended member having projections thereon, a lever to which the weight to be lifted is attached, two hooks pivoted to said lever on opposite sides of the attachment point of said weight, said hooks engaging the projections on said suspended member from opposite sides, spring means for forcing said hooks toward each other, a finger secured to one of said hooks, and a lowering cam carried by the other hook and engaged by said finger to lift said hooks alternately out of engagement with the projections on said member as said lever is operated.
- 10 7. A weight lifting device comprising a suspended member having projections thereon, a lever to which the weight to be lifted is attached, two hooks pivoted to said lever on opposite sides of the attachment point of said weight, said hooks engaging the projections on said suspended member from opposite sides, spring means for forcing said hooks toward each other, a finger secured to one of said hooks, a lifting cam engaged by said finger and so formed as to throw said hooks alternately out of engagement with said projections as said hooks are lifted without preventing said hooks from engaging said projections as they are lowered, and a lowering cam engaged by said finger and so formed as to prevent said hooks from engaging said projections when at or near their upper position.
- 15 8. A weight lifting device comprising a suspended member having projections thereon, a lever to which the weight to be lifted is attached, two hooks pivoted to said lever on opposite sides of the attachment point of said weight, said hooks engaging the projections on said suspended member from opposite sides, spring means for forcing said hooks toward each other, a finger secured to one of said hooks, and a lifting cam engaged by said finger and so formed as to throw said hooks alternately out of engagement with said projections as said hooks are lifted without preventing said hooks from engaging said projections as they are lowered.
- 20 9. A weight lifting device comprising a suspended member having projections thereon, a lever to which the weight to be lifted is attached, two hooks pivoted to said lever on opposite sides of the attachment point of said weight, said hooks engaging the projections on said suspended member from opposite sides, spring means for forcing said hooks toward each other, a finger secured to one of said hooks, and a lifting cam engaged by said finger and so formed as to throw said hooks alternately out of engagement with said projections as said hooks are lifted without preventing said hooks from engaging said projections as they are lowered, and a lowering cam engaged by said finger and so formed as to prevent said hooks from engaging said projections when at or near their upper position.
- 25 10. In testimony whereof, I have hereunto set my hand at Los Angeles, California, this 17th day of June, 1920.

EARL E. CHAPMAN.
